UNITED STATES PATENT OFFICE.

JOSIAH A. HARD, OF DENVER, COLORADO.

CAN-HOLDER AND DRIP-PAN.

SPECIFICATION forming part of Letters Patent No. 367,342, dated July 26, 1887.

Application filed March 11, 1887. Serial No. 230,569. (No model.)

To all whom it may concern:

Be it known that I, JOSIAH A. HARD, of Denver, in the county of Arapahoe and State of Colorado, have invented certain new and 5 useful Improvements in Can-Holders and Drip-Pans combined; and I do hereby declare that the following is a full, clear, and exact description thereof, reference being had to the accompanying drawings, making a part of this specification.

My invention relates to an improved device for supporting cans containing liquid and receiving the drippings from said cans; also to greatly facilitate the emptying of the cans into 15 other receptacles, such as lamps, cups, pails, &c.

It consists of a sheet-metal base, to which is attached an upright containing two horizontal parallel arms which terminate in small hooks. 20 Between these arms and in the terminating hooks is supported, a short distance above the base, a can, to which short shoulders, or suitable projections have been attached, one on each side, the parts being arranged and adapted 25 to operate as will be hereinafter more fully described.

Referring to the drawings, Figure 1 is a perspective view of my invention, also showing a can in position at rest. Fig. 2 is a sectional 30 view of the can, showing the shoulders or projections that rest in the hooks of the arms. Fig. 3 is a sectional front view of the upright. Fig. 4 is a sectional side view of the invention.

Similar letters of reference occurring on the 35 several figures indicate corresponding parts.

d represents the back part of the base, which is also a shallow pan for receiving the drippings from the can.

D represents a narrow flat continuation of 40 the base in front of the upright. This is made narrow to allow a lamp or other receptacle to be held sufficiently near the tilted can to receive its contents.

B, in the different figures, represents the up-

right attached to the base, on which the parallel horizontal arms *b b* are formed or attached, which terminate in the small hooks *c c*, in which the shoulders or projections *a a* are inserted and rest while using the can in connection with my invention. 45

In the practical use or operation of my invention the can is tilted by elevating the lower portion of the can by its strap or handle at the back part, which causes the nozzle or front of the can to descend over the front groove of the 55 upright and base toward a lamp or other receptacle held by the other hand in readiness for filling.

With my invention a child can fill a lamp from a full can with the utmost ease and accuracy. The liability of spilling the liquid on the outside of the receptacle to be filled, or on the table, floor, &c., is entirely done away with. The points of the hooks *c c* are bent sufficiently forward toward the upright to prevent my device from slipping off the shoulders or projections *a a* on the can. Thus the device can be lifted by the bail of the can. 60

As long as the can is connected with my invention there is no risk of soiling floors, tables, &c., by the seeping or dripping oil or other liquid. 70

Having thus described my invention, what I claim as new, and desire to secure by Letters Patent, is— 75

As a new article of manufacture, the hereinbefore-described tilting can-holder and drip-pan combined, consisting of the base *D*, drip-pan *d*, upright (shaped as shown) *D*, horizontal arms *b b*, and hooks *c c*, substantially as 80 described and shown.

In testimony that I claim the foregoing I have hereunto set my hand this 24th day of February, 1887.

JOSIAH A. HARD.
